CLAIM

The ornamental design for a footboard top corner edge, as shown and described.

DESCRIPTION

FIG. 1 is a front elevational view of a footboard top corner edge showing my new design.

FIG. 2 is a left-side elevational view thereof.

FIG. 3 is a right-side elevational view thereof.

FIG. 4 is a top plan view thereof.

FIG. 5 is a rear elevational view thereof; and,

FIG. 6 is a bottom elevational view thereof.

The broken lines in FIGS. 1-6 depict environment and form no part of the claimed design.

The claimed design does not include any depth.
